HIGH SPEED MECHANICAL MOTION

Charles E. Branscomb, Endwell, N.Y., assignor to International Business Machines Corporation, New York, N.Y., a corporation of New York

Application June 30, 1958, Serial No. 745,404

5 Claims. (Cl. 164—111)

This invention relates to a new and useful improvement in apparatus for producing high speed mechanical motion and more particularly to a device for obtaining cyclic, selectable, high speed mechanical motion.

There are many machines that require a device capable of imparting very high speed mechanical motion over short distances to selectable elements and additionally to cause said motion to be accurately timed with respect to other operating elements within the machine. The invention is capable of higher operating speeds than present devices through a novel combination of means to select the element to be moved, a continuously rotating cam device to cooperate with said selection means and further to directly supply the operating force rather than a start-stop mechanism, and a low inertia linkage system for delivering the operating force to the member to be moved.

It is an object of the invention, therefore, to provide high speed mechanical motion.

Another object of the invention is to provide cyclic, selectable, high speed mechanical movement.

A further object of the invention is to provide cyclic, accurately timed mechanical movement.

Yet another object of the invention is to provide means to positively restore the selecting means at the end of an operating cycle.

Other objects of the invention will be pointed out in the following description and claims and illustrated in the accompanying drawings, which disclose, by way of example, the principle of the invention and the best mode, which has been contemplated, of applying that principle.

In the drawings:

Fig. 1 is a sectional view through punching mechanism incorporating the novel device.

Fig. 2 is a cross sectional view along the lines 2—2 of Fig. 1.

Fig. 3 is a layout view of the control cam.

Fig. 4 is a schematic of the control circuit of an interposer magnet.

The invention is adaptable for use in many types and classes of machines. As an example, but not limited thereto, many data processing machines require high speed, cyclic, accurately timed, short travel mechanical motion during sorting, punching, and printing operations.

As a particular illustration the invention will be explained in conjunction with perforating machines of the class disclosed in U.S. Patent No. Re. 21,133, dated June 27, 1939, but it should be understood that the device is useful in any machine requiring cyclic, selectable, high speed mechanical movement.

As used in the perforating machine which has been chosen, by way of example, the invention provides selective motion of an interposer into the path of a punch operating bail. Referring now to the drawings, Fig. 1 shows an eccentric shaft 18 and a punch operating bail 16 for selectively operating a plurality of punches, one of these being shown at 10 in Fig. 1. Articulated

2

to the punch 10 is an interposer 11 to which is connected one end of interposer belt 19. The belt 19 passes over an interposer control cam 20 and is anchored at its opposite end at 22. A related interposer magnet 21 has an armature 23 bearing laterally upon the belt 19.

A reciprocating motion will be imparted to punch operating bail 16 through link 17 by the eccentric rotation of shaft 18. Suitable driving means may be used to provide continuous rotation of shaft 18. When not operated on by belt 19, interposer 11 is constrained by spring 12 from movement into the path of the continuously reciprocating punch operating bail 16. Interposer belt 19 may be of any suitable material, viz., metal, plastic, or fabric, which has sufficient tensile strength to endure cyclic stressing. Belt 19 may have a round, square, or flat cross sectional configuration.

Cam 20 is geared to the same driving means, through gears 26, 27, and 28 that supplies rotation to the eccentric shaft 18 so that cam 20 makes one revolution for each revolution of eccentric shaft 18. Each punch cycle includes therefore, one rotation of eccentric shaft 18, one reciprocating operation of punch operating bail 16, and one rotation of the interposer control cam 20.

The interposer belt 19 is positioned on the surface of cam 20. As indicated in the illustrative example shown in Fig. 2, a plurality of belts 19 and cams 20 may be arranged for use with an eighty punch perforating machine, as for example that shown in Patent Re. 21,133. The coaction of the interposer wire and interposer control cam may be explained with reference to Fig. 2 and Fig. 3. As shown in Fig. 3, a first sector of the cam surface is divided into two parallel tracks 30 and 31 and a second sector of the cam surface has a single track 32 formed by the junction of tracks 30 and 31.

Together tracks 30 and 32 form a first complete path over the cam surface having a circular shape and tracks 31 and 32 form a second complete path having an ovate shape. Normally the interposer belt is positioned by armature 23 to contact the surface of the interposer control cam along said first path. Because the path formed by tracks 30 and 32 is circular, no motion is imparted to the interposer belt by the rotation of the interposer control cam. The magnet 21 is energized at the proper time in the cycle of cam 20 by a circuit (Fig. 4) extending from the positive side of the line through a cam operated contact 41, a selector contact 40, magnet 21, and fuse 42 to the negative side of the line. The cam which operates contact 41 is geared to run synchronously with cam 20 so that it closes contact 41 just as belt 19 is approaching the bifurcation of track 32 into tracks 30 and 31. When magnet 21 is energized its armature 23 shifts belt 19 from track 30 to track 31. Synchronization of cam operated contact 41 with the punch operating bail 16 and the cam 20 is accomplished by gearing

(not shown) similar to that which synchronizes cam contacts C15 and P1 with punch bail mechanism disclosed in Patent Re. 21,133. While the armature is laterally moving the belt across the surface of the interposer control cam, rotation of the cam brings projection 34, formed by the intersection of tracks 30 and 31, in contact with interposer belt 19. Projection 34 is so shaped as to positively position interposer wire 19 in track 31 upon continued rotation of interposer control cam 20. Track 31 has a first portion of increasing radius and a second portion of decreasing radius. The increased radius of track 31 as compared with the constant radius of track 30, applies a tension to belt 19. The belt being rigidly anchored at 22 the tension is exerted through interposer 11 upon spring 12. Additional rotation of interposer cam 20 increases the tension in interposer belt 19 sufficiently to overcome the tension of spring 12 causing interposer 11 to move to the right to engage the

70

punch operating bail 16 in the notch 24. The continued downward motion of punch operating bail 16 and engaged interposer 11 forces punch 10 through stripper 15, card 25 and into die 14. Continued rotation of control cam 20 maintains the tension in interposer belt 19, causing the interposer 11 to remain positively engaged with the punch operating bail 16.

Upon the start of the upward motion of punch operating bail 16, interposer belt 19 is in contact with the hereinbefore mentioned decreasing radius portion of track 10 31. Further rotation of interposer control cam 20 continues to reduce the tension applied to interposer belt 19 and additionally causes the belt to laterally move to the path consisting of tracks 30 and 32 through the action of shaped projection 33. The restoring of belt 19 to the circular track by the projection 33 also acts to restore armature 23 to its normal deenergized position. Concurrently with the restoring of interposer belt 19 and armature 23, interposer 11 is also restored to its normal position by means of the combination of spring 12 and interposer knock off bar 13.

Although the invention has been described, by way of example, with reference to certain punch apparatus, it should be understood that the principle of the invention may be applied to other types and classes of machines that require cyclic, selectable high speed mechanical movement.

While there have been shown and described and pointed out the fundamental novel features of the invention, it will be understood that various omissions and substitutions and changes in the form and details of the device illustrated and in its operation may be made by those skilled in the art, without departing from the spirit of the invention. It is the intention, therefore, to be limited only as indicated by the scope of the following claims.

What is claimed is:

1. In a device for imparting to a movable object, cyclic, selectable, high speed mechanical movement, the combination comprising a rotary cam having a constant radius controlling surface and a varying radius controlling surface, a belt looped over said cam and adapted to ride on either of said controlling surfaces alternatively, means to anchor one end of said belt in fixed relation to the axis of rotation of said cam, means to connect the other end of said belt to the object to be moved, means to apply a yielding force to the object tending to pull said belt against said cam, and means to shift said belt alternatively from one controlling surface to another.

2. The device of claim 1 wherein said varying radius controlling surface includes means, in combination with said shifting means, to shift said belt to said constant radius controlling surface.

3. In a device for imparting to a movable object, cyclic, selectable, high speed mechanical movement the

5 combination comprising a rotary cam having a circular controlling surface and an elliptical controlling surface, a belt looped over said cam and adapted to ride on either of said controlling surfaces, means to anchor one end of said belt in fixed relation to the axis of rotation of said cam, means to connect the other end of said belt to the object to be moved, means to apply a yielding force to the object to be moved tending to pull said belt against said cam, means to normally position said belt on said circular controlling surface, said positioning means being selectively operable during a predetermined arc of travel of said cam to position said belt on said elliptical controlling surface.

4. A punch mechanism comprising a punch, an interposer positionable to select said punch for operation, a belt, a rotating cam having two peripheral controlling surfaces, the first of said controlling surfaces having a circular circumference, the second of said controlling surfaces having an elliptical circumference, means to connect one end of said belt to said interposer, means to anchor another end of said belt, spring means applied to said interposer and said belt tending to maintain said belt on said first controlling surface, means selectable during a first predetermined portion of each cycle of 15 rotation to shift said belt from said first controlling surface to said second controlling surface, said second controlling surface having associated therewith a portion tending to return said belt to said first controlling surface during a second predetermined portion of each 20 cycle of operation.

5. In a punching mechanism, a punch operating member, a punch member including an interposer adapted to be moved to engage said punch operating member to cause said punch to be operated by the latter, a rotating 25 cam member, means to drive said punch operating member and said cam member in synchronism, a belt looped over said cam member and having one end fixed in relation to the axis of rotation of said cam member and the other end connected to said interposer, means applying 30 a yielding force to said interposer tending to hold the same disengaged from said punch operating member and to maintain said belt in tension, said cam member having two peripheral cam surfaces adapted to receive said belt 35 alternatively, one of said surfaces being concentric to the axis of rotation of said cam member and the other being eccentric thereto, means for shifting said belt from one to the other of said cam surfaces, and means for operating said shifting means when said cam is in a predetermined angular position.
